MANUALLY OPERATED SOUND
REPRODUCER

Mathew A. Strumor, Brooklyn, N. Y.

Application April 27, 1946, Serial No. 665,553

5 Claims. (Cl. 274—1)

1

This invention relates to sound reproducing devices, and more particularly to devices mounted in toy animals, dolls, etc. which, upon pressing in of a part of the body, cause a sound to be given off.

One object of the invention is the provision of a sound producing device adapted to be used as above-mentioned and to have the sound produced by passing a needle over a sound track.

Thus the sound to be produced may be that particularly characteristic of the toy figure in which the device is mounted. For instance, if the device is mounted in a doll, the sound track will contain a recording of a baby's actual crying of "mama"; if it be mounted in a dog, the recording will be actually that of the barking of a dog; etc.

The above as well as additional objects will become apparent in the following description, wherein characters of reference refer to like-numbered parts in the accompanying drawing. It is to be noted that the drawing is intended for the purpose of illustration only, and that it is neither desired nor intended to limit the invention necessarily to any or all of the details of construction shown excepting insofar as they may be deemed essential to the invention.

Referring briefly to the drawing, Fig. 1 is a representation of a doll, adapted to have the device of the invention mounted in the body thereof, shown in broken lines.

Fig. 2 is a front view of the device.

Fig. 3 is a longitudinal sectional view taken on the line 3—3 of Fig. 2.

Fig. 4 is an enlarged plan view, partly in section, of the sound track axial rod, the needle, the diaphragm wall of the slidable cylinder, and the supporting wall of the stationary cylinder, partly in section, which may also be considered a sectional view taken on the line 4—4 of Fig. 3.

Fig. 5 is a cross-sectional view taken on the line 5—5 of Fig. 4.

Fig. 6 is a fragmentary cross-sectional view taken on the line 6—6 of Fig. 5.

Referring in detail to the drawing, the numeral 10 indicates a representative figure, in this case a doll, which is adapted to have the device of the invention mounted therein in such manner that, when the stomach is pressed inward, the sound recorded in the sound track of the device will be reproduced as coming from the figure 10. The device is shown in broken lines at 11 in Fig. 1.

The device comprises a stationary cylinder 12

on its front end; the cylinder 12 is adapted to be anchored or secured within the body of the figure 10 in any suitable manner, not shown, so long as it will remain stationary and will be positioned so that the forward extremity of the device, to be described, will lie in or closely adjacent to an accessible part of the body of the figure 10, such as, for instance, the stomach.

An axial rod 15, which may be cylindrical or of other desired cross-section or conformation, is anchored in or to the wall 13 in any desired manner, such as, for instance, by means of screws 16. A cylinder 17 is in slidable engagement within the cylinder 12, being provided with the enlarged limit stop or flange 18 whose function is obvious. The outer end of the cylinder 17 is closed by a screen or other perforated cover 19 which may be simply secured in any desired manner about the cylinder, or it may be, as shown, secured to a threaded ring 20 adapted to be screwed about the threaded periphery of the cylinder 17.

The rear wall 21 of the cylinder 17 has an axial opening 22 therethrough and serves as a sounding diaphragm, as will be presently described. A coiled spring 23 within the stationary cylinder 12 normally urges the slidable cylinder 17 to its extreme outward position shown in Fig. 3.

The upper surface of the rod 15 is here shown flattened into a plane 24, and an endless groove 25 is cut thereinto, one side of the endless groove being shown at 26 and the other at 27, and both of these are shown straight and parallel. At both ends the grooves are joined by curved sections 28 and 29.

Anchored to the diaphragm wall 21 in any suitable manner is the base of an arm 30 which may be of steel, and whose free end 31 is deformed substantially as shown to extend axially into the groove 25, the extremity of the said free end being sharpened or tapered to form a needle 32.

The groove 26 contains a sound track 27a, indicated by the transverse marks shown in Fig. 4. It is apparent that as the cylinder 17 moves inward as a result of pressure applied on the stomach of the figure 10, the needle 32 travels down the groove 26 in engagement with the sound track 27a, thereby reproducing in the diaphragm 21 the recording of the sound track and causing the reproduced sound to pass through the screen 19 to become audible outside the figure 10.

Assuming that the cylinder 17 is forced inward, against the spring 23, as far as it will go, it will carry the needle 32 to substantially the position

shown in broken lines at 32a in Fig. 4, and the cylinder 17 will have been rotated through a small arc. For this movement of the cylinder, it may be desirable that the ring 20 have free rotatable engagement with the cylinder 17, instead of the threaded engagement shown, although that should not be necessary as long as the ring is not locked to the stomach of the figure 10. If, then, pressure on the cylinder 17 is withdrawn, the spring 23 will move it outward, and as the needle 32 is in the position 32a it will naturally enter the groove 27, which is smooth and therefore silent, for its return movement. When the cylinder reaches its outward limit stop, the needle 32 will rest in the position 32b, ready for passage down the track on repetition of the cycle, after the same arcuate rotation of the cylinder 17 in the reverse direction.

As an aid in switching the needle from the groove 26 to the groove 27, and vice versa, if desired, in the connecting grooves 28 and 29, additional means may be provided. One form of said means is shown in the form of leaf springs 33 and 34 anchored in grooves cut into the surface 24, and extending across the end grooves 28 and 29. As the needle reaches the end of its stroke in either direction, the spring 33 or 34 will act as a cam when the stroke is reversed, as is obvious from Fig. 4.

The idea of the invention as illustrated and described may of course be carried out in other ways than above set forth. In actual practice, the device 11 may be provided with different recordings on its sound track 27a, according to the kind of toy or figure in which it is to be mounted. Hence the figure may be made to emit a sound consistent with its nature, instead of merely a squeak or other sound or distant simulation of the sound it makes by nature. Whence it follows that a child will be far more pleased with his or her toy or doll, especially when it is considered that the sounds emitted by many such articles is hideous and often frightening to the child.

Obviously, modifications in form and structure may be made without departing from the spirit and scope of the invention.

The needle arm 30 may be made substantially rectangular in cross-section, that is, in the form of a band which is adapted to flex upwards substantially as shown in broken lines in Fig. 6. Moreover, the tip of the needle 32 may be shaped approximately in the fashion of the tip of a semi-cone, rounded around the extremity, with the rounded portion 34a thereof on the right side of the needle (Fig. 6) and the sharpened surface of the needle point on the left side. Then, in the event that the cylinder 17 is pushed only, say, half-way home into the cylinder 12, and then released, one of two things will happen to the needle, either it will ride back along the sound track 27a with the rounded portion 34 thereof riding freely over the rough sound track without wearing the latter, or, if the needle should stick in the track, the flexibility of the arm 30 will permit the latter to flex upward while the needle extension 31 swings through the arc shown in Fig. 6 and assumes the position shown in broken lines. In the latter case the needle will ride back with the rounded surface 34a thereof riding over the sound track without digging into the track to damage the same.

I claim:

1. A sound emitting device comprising a cylinder having a rigid member longitudinally mount-

ed therein in fixed position, a second cylinder slidably mounted within said first cylinder, the front end of said first cylinder being open, means normally urging said second cylinder outward through said front end of said first cylinder, the rear end of said second cylinder having a wall closing the same and having an opening therein, a rod secured in said first cylinder and registering slidably in said opening, said rod having a longitudinal groove therein containing a sound track, a needle secured by its base to said rear wall of said second cylinder and having its tip registering in said track.

2. The device set forth in claim 1, said rod having a second longitudinal groove spaced from and substantially parallel with said first groove, connecting grooves between said first and second grooves at the ends of the latter, said connecting grooves having approximately the shape of an arc of a spiral with the arc of one of said connecting grooves being directed oppositely to that of the other of said connecting grooves whereby when said second cylinder reaches the end of its stroke in either direction the said connecting groove at that end will guide the tip of said needle toward the entrance to the other of said longitudinal grooves, said second cylinder being free to rotate through an arc.

3. The device set forth in claim 1, said rod having a second longitudinal groove spaced from and substantially parallel with said first groove, connecting grooves between said first and second grooves at the ends of the latter, said connecting grooves having approximately the shape of an arc of a spiral with the arc of one of said connecting grooves being directed oppositely to that of the other of said connecting grooves whereby when said second cylinder reaches the end of its stroke in either direction the said connecting groove at that end will guide the tip of said needle toward the entrance to the other of said longitudinal grooves, said device having releasable locking means interposed in said connecting grooves constraining said needle tip from reverse movement back into either of said longitudinal grooves upon return of said second cylinder after reaching the end of its stroke.

4. The device set forth in claim 1, said base of said needle forming an angle with said tip, said base extending from said rear wall of said second cylinder at substantially right angles to the latter, said base being substantially rectangular in cross-section thereby increasing the flexibility of said base, said needle tip lying in a plane at right angles to the wider pair of opposed surfaces of said rectangular base.

5. The device set forth in claim 1, that side of the tip of said needle facing toward said rear wall of said second cylinder being rounded.

MATHEW A. STRUMOR.
